UNITED STATES PATENT OFFICE.

GEORGE AID AND FREDERICK AID, OF GALLATIN, MISSOURI.

NECK-YOKE CENTER.

No. 823,575.

Specification of Letters Patent.

Patented June 19, 1906.

Application filed December 20, 1905. Serial No. 292,564.

To all whom it may concern:

Be it known that we, GEORGE AID and FREDERICK AID, citizens of the United States, residing at Gallatin, in the county of Daviess and State of Missouri, have invented certain new and useful Improvements in Neck-Yoke Centers; and we do hereby declare that the following is a full, clear, and exact description of the same, reference being had to the annexed drawings, making a part of this specification, and to the letters of reference marked thereon.

The present invention has for its object to provide a neck-yoke center that will be simple in construction and effective in its purpose in preventing the same from pounding the pole and adding materially to the general usefulness of the device.

The invention consists in a neck-yoke center constructed substantially as shown in the drawings and hereinafter described and claimed.

Figure 1 of the drawings is a perspective view of a neck-yoke center constructed in accordance with our invention; Fig. 2, a side elevation, partly in section, showing the pole in engagement with the pole-ring; Fig. 3, a transverse sectional elevation taken on line 3-3 of Fig. 2; Fig. 4, a sectional view showing a modification; Fig. 5, a detail perspective view of the cam-block.

In the accompanying drawings, A represents the usual yoke-band of any preferred construction, and B the ring to which the vehicle-pole is connected, as indicated at C. The yoke-band A has ears or flanges a, between which is secured the eye b of the presser-block D, which forms a part of the locking device, a bolt or other suitable fastening c connecting the eye with the flanges of the yoke-band. The locking device consists of two parts—viz., the presser-block D, hereinbefore described, and the cam-block E, the cam-block being operated by the presser-block to force the former down with frictional contact upon the pole C.

It will be noticed in Fig. 2 of the drawings that a space is left between the under side of the presser-block D and the upper side of the cam-block E, as indicated at d, which will admit of the presser-block to rock slightly back and forth, and when the outer end of the presser-block comes in contact with the cam-block it will cause the latter to press on the vehicle-pole, which locks on same and prevents the neck-yoke center slipping from the

pole should the traces become broken or detached. The under side of the cam-block is concave to correspond with the convexity of the pole, as indicated at e, so that the under side of the cam-block will come in frictional contact with the vehicle-pole when pressed down by the presser-block. The presser-block D and the cam-block E are suitably connected by a bolt or other suitable fastening f to the vehicle-pole ring B between the ears or flanges g thereof. Any suitable means, however, may be employed for pivotally connecting the presser-block D to the yoke-band A and to the vehicle-pole ring B and suitable means employed for pivotally connecting the cam-block E to said pole-ring as found best adapted to the purpose, and in the present instance is shown the bolt f, extending through holes in the ears or flanges g of the pole-ring and through suitably-formed holes in ears or flanges h of the cam-block, the presser-block being located between the ears, as shown.

The cam-block E may be constructed in two longitudinal sections, as indicated in Fig. 1 of the drawings, to facilitate casting or may be made in a single piece, as shown in Fig. 5 of the drawings, as found most preferable, as we do not wish to confine our invention to any particular means of construction.

In place of the ears or flanges h upon the cam-block E said flanges may be on the presser-block D and the cam-block formed with a central web, said flanges and central web being shown at i, j, respectively, in Fig. 4 of the drawings, the same result being obtained as in the construction shown in Fig. 1 of the drawings. The holes k in the ears or flanges h of the cam-block D may be of such form as to admit of a little clearance or space between the outer ends of the presser-block and the end of the cam-block, as indicated at d, hereinbefore referred to, thus allowing of the cam-block to rock slightly back and forth, round or elongated holes being used as found most preferable. When a round hole is used, it should be slightly larger in circumference than the circumference of the fastening-bolt to admit of this rocking movement of the cam-block and when elongated holes are used, as shown in Fig. 5 of the drawings, it will allow the cam-block to be pressed down on a smaller vehicle-pole, giving a longer bearing.

The blocks D and E, as will be noticed, are pivotally connected to the ears or flanges g

of the vehicle-pole ring B by one and the same bolt or pivot-pin, and the length and width of the bearing or concave face of the cam-block E provides a long and broad bearing on the vehicle-pole which prevents it from cramping the same. It is evident that both the blocks D and E may be constructed in any suitable manner found most preferable without in any manner departing from the essential features of the invention and any changes or modifications as would come within ordinary mechanical judgment may be resorted to and still come within the scope of the invention.

Having now fully described our invention, what we claim as new, and desire to secure by Letters Patent, is—

A neck-yoke center comprising a yoke-band and pole-ring, a cam-block having a

concave bearing-face upon its under side extending the entire length thereof and provided with upwardly - projecting ears, a presser-block located between the ears of said bearing, a single pivot connecting the cam-block and the presser-block together and to the pole-ring, the ends of said blocks extending out beyond the pole-ring and the presser-block pivotally connecting with the yoke-band, substantially as and for the purpose set forth.

In testimony whereof we affix our signatures in presence of two witnesses.

GEORGE AID.
FREDERICK AID.
